UNITED STATES PATENT OFFICE.

THOMAS C. HACKETT, OF QUEEN ANNE, MARYLAND, ASSIGNOR OF TWO-THIRDS TO HOWARD R. HOPKINS, OF WYE MILLS, AND CATHERINE HACKETT, OF HILLSBOROUGH, MARYLAND.

SPRING-KEY THREADLESS BOLT.

SPECIFICATION forming part of Letters Patent No. 633,719, dated September 26, 1899.

Application filed November 28, 1898. Serial No. 697,622. (No model.)

To all whom it may concern:

Be it known that I, THOMAS C. HACKETT, a citizen of the United States, residing at Queen Anne, county of Queen Anne, State of Maryland, have invented certain new and useful Improvements in Spring - Key Threadless Bolts; and I do hereby declare the following to be a full, clear, and exact description of the invention, such as will enable others skilled in the art to which it appertains to make and use the same.

This invention relates to means for fastening railway-rail joints; and it consists, substantially, in such features of improvement as will hereinafter be more particularly described.

The object of the invention is to dispense with the use of washers and threaded bolts and nuts as elements in a rail-joint fastening and to substitute therefor devices which can be applied more quickly and which operate with greater effectiveness in maintaining a tight joint or connection between the ends of the rails.

A further object is to provide a fastening for rail-joints which cannot readily be released or disconnected without the use of a specially-contrived device or implement for that purpose.

These and additional objects I attain by the means illustrated in the accompanying drawings, in which—

Figure 1 is a side view of two rails joined or spliced by means of my improved fastening device. Fig. 2 is a cross-sectional view on the line *x x*, Fig. 1, and showing more clearly the construction and operation of the several parts. Fig. 3 is a detailed view of the bolt and its fastening devices in top plan view. Fig. 4 is a similar view in bottom plan

and showing very clearly the manner of employing the tool or special implement for disconnecting and removing the spring-clamp from the bolt. Fig. 5 is a top plan view of Fig. 1, showing the bolt and its fastener in a position at right angles to that shown in Figs. 1 and 2. Fig. 6 is a view showing the tool or implement employed for disconnecting the fastening for the bolt.

Preliminarily to a more detailed description it may be stated that my invention comprises a threadless bolt passing through the fish-plates and the rail and so constructed as to be incapable of turning in the said plates, yet permitting sufficient movement of the rails to allow for expansion and contraction of the latter. Said bolt is provided with means constantly tending to tighten the same, and said means also constantly tend to tighten the fish-plates against the rails, so that the latter are effectually prevented from separation or dislodgment at the joint.

My invention is capable of a great many different embodiments, and it will be understood that the same can be used with equal effect as a fastening for almost any of the known forms of joints in which splice-pieces are used for connecting or joining together two or more parts.

Reference being had to the accompanying drawings, A A represent two railway-rails, and B B' represent fish-plates or splice-pieces arranged on either side of said rails and overlapping the same at the joint or abutting ends thereof. Said fish-plates are adapted to fit snugly against the webs *a* of the rails in the usual manner, and they are formed on opposite sides of the rail-joint *b* with corresponding openings *c*. Said openings are elongated lengthwise of the plates, and they are practically oblong in shape, having no angles, however, which would tend to weaken the plates. The web *a* of each of the rails A is formed with a similarly-shaped opening *d*, enabling the proper insertion of the bolt at the time of applying the fastening, and these openings *d* permit of a limited movement of the rails to allow for expansion and contraction thereof.

Inserted in the openings *c* and *d* on either side of the rail-joint *b* is a threadless bolt D, which in part constitutes my present improvements. The said bolt is formed with a head *e* and a short section or portion *f*, which, as shown at *g g*, is flattened on opposite sides to correspond with the upper and lower edges of the said opening *c*. The bolt is further formed with a longer or extended portion *h*,

similarly flattened on opposite sides, as shown at *i i*, and an intermediate connecting portion *j*. The latter portion is substantially round in cross-section and, as seen at *j'* and *k*, respectively, the rounded sides *l* of the sections or portions *f* and *h* project beyond the sides of the said rounded portion *j'*. In this way shoulders are formed which prevent the flattened portions of the bolt from entering the opening *d* in the web after the fastening has been properly applied and the parts adjusted. As shown in Fig. 2, the portion *f* of the bolt fits snugly in the opening *c* of fish-plate *B* and the portion *h* thereof similarly fits the corresponding opening in plate *B'* and projects beyond the said plate. The intermediate round portion *j'* is received by the opening *d* in the web of the rail and the rail is free to move thereon to a limited extent.

From the construction and arrangement shown and described it is apparent that neither the bolt nor the fish-plates can turn when the parts are in position. Instead of forming the bolt with the intermediate rounded portion *j'* I could form the same of equal dimensions with the portions *f* and *h* throughout; but in that case the opening *d* in the web *a* would have to be made correspondingly longer, which would tend to weaken the rail and which it is the purpose of the present construction to avoid. The bolt has a reduced end portion *3* and is notched or grooved at *11*, the purposes of which will be explained hereinafter.

In connection with my improved form of threadless bolt *D*, I employ devices operating automatically to take up the wear of the parts resulting from vibration produced by trains moving upon the rails, and said devices also prevent the bolt and fish-plates from working loose from other causes. Thus I form in the extended flattened portion *h* of the bolt an elongated opening or slot *m*, the end wall *n* of which is straight, as shown, and the opposite wall *n'* of which is beveled or inclined. Fitting in the said opening or slot is a key or wedge *o*, having a straight edge *o'*, corresponding to wall *n*, and a beveled or inclined edge *o''*, corresponding to wall *n'*, while the upper edge of said key or wedge is rounded off at *o³* for a purpose to be described. The said opening *m* on opposite sides of the bolt is partially covered or overlapped by the upper and lower edges of opening *c* in fish-plate *B'*, as shown, so that the key or wedge is held in the opening, with the straight edge thereof bearing or resting against the side of the fish-plate on opposite sides of the bolt. It is only by continued wear of the fish-plate or some other part that the key or wedge is permitted to descend farther into the opening, and it is evident from the arrangement shown that such wear will be taken up by the key for a considerable length of time.

In order to prevent the key or wedge from being dislodged from the opening *m* and also

to insure the automatic action thereof, I provide means constantly exerting a pressure thereon to force the same into the opening as any wear occurs. Said means consist of a powerful spring-clamp *G*, formed with a portion *1*, having a rectangular opening *2*, and fitting upon the reduced end *3* of the bolt, which is also rectangular, as shown, and which is preferably beveled at *4* to facilitate insertion of the same in the said opening *2*. By so reducing the bolt at the end a shoulder is formed at *5* for the clamp to abut against, and which also limits the extent to which the clamp can be forced onto the bolt. The said clamp is also formed with a portion or jaw *6*, turned inward from the said portion *1*, substantially at right angles thereto, and with a longer portion or jaw *7*, also turned inward therefrom in the same manner. The said jaw *7* bears upon the upper edge of the key or wedge *o* and is struck up at *8* to form a groove *9* to partially receive the said key, and the said jaw *6* is turned inward at the end to form a lip *10*, which is received by the groove *9* or notch *11* in the corresponding side of the bolt. One edge of the opening *2* is turned outward to form a lip *12*, which gives greater bearing for the clamp upon the reduced end portion *3* of the bolt. The clamp is simply forced onto the end of the bolt until the lip *10* enters the groove *11*, whereupon the parts are securely clamped in position and the jaw *7* continues to exert a pressure upon the key to force the same farther into the opening *m*. The rounded upper edge of the key enables the jaw *7* to ride upon the same when the clamp is forced onto the bolt.

The clamp can very readily be forced into place by hand; but purposely the construction and arrangement are such as to render it extremely difficult and in some instances altogether impossible to remove the same without the use or aid of some implement. For this purpose I use the tongs *M*, (shown in Fig. 6,) which, as shown, consists of two jaws *v*, each wedge-shaped in cross-section and each having a handle portion *w*, bent or turned at *x* to constitute hooks for the reception of the fingers. The said handle portions are pivoted together at *y*, and by spreading the same apart the jaws *v* are separated or also spread apart. To disconnect and remove the spring-clamp *G*, the tongs are applied, as shown in dotted lines, Fig. 4, by inserting the jaws *v* between the bolt and the jaw *6* of the clamp, and then the handle portions are pressed together firmly, whereupon as the said jaws are forced together or toward each other the said jaw *6* of the clamp is forced outward and the lip *10* thereof disengaged from the groove *11*. By now pulling upon the tongs the said clamp will be withdrawn from the bolt, and the latter can then be removed after the removal of the key *o* from the opening *m*.

Instead of arranging the bolt and its fas-

tening devices in the position shown in Fig. 2 I sometimes arrange the same at right angles thereto, as shown in Fig. 5, in which case it is only necessary to extend the openings *c* vertically instead of horizontally.

It will of course be understood that the details of construction of the several parts can be varied without departing from the spirit of my invention.

10. What I claim is—

1. The combination with the rails and fish-plates, of a threadless bolt passing therethrough on either side of the rail-joint, a key or wedge working in the bolt, and engaging 15 one of the fish-plates, and means carried by the bolt exerting a constant pressure on the key.

2. The combination with the rails and fish-plates, of a threadless bolt passing therethrough on either side of the rail-joint, a key or wedge working in the bolt, and engaging 20 one of the fish-plates on opposite sides of said bolt, and means carried by the bolt exerting a constant pressure on the key.

25. 3. The combination with the rails and fish-plates, of a threadless bolt passing therethrough on either side of the rail-joint, a key or wedge working in the bolt, and engaging the side of one of the fish-plates, and a spring-30 clamp fitting upon the bolt and exerting a constant pressure upon the key.

4. The combination with the rails and fish-plates, of a threadless bolt passing therethrough on either side of the rail-joint, and 35 having a notch in one side thereof, a key or wedge working in the bolt, and engaging the side of one of the fish-plates, and a spring-clamp exerting a constant pressure on the key and having a jaw engaging the notch in 40 the bolt.

5. The combination with the rails and fish-plates, of a threadless bolt passing therethrough on either side of the rail-joint, a key or wedge working in the bolt, and engaging 45 the side of one of the fish-plates, and a spring-clamp having one jaw engaging the bolt and another jaw exerting a constant pressure on the key.

6. The combination with the rails and the 50 fish-plates, of a threadless bolt passing therethrough on either side of the rail-joint, and formed at the end with a reduced portion and a shoulder, a key working in said bolt and engaging the side of one of the fish-plates, 55 and a spring-clamp fitting said reduced portion and abutting against the shoulder, and

formed with a jaw exerting a constant pressure upon the key.

7. The combination with the rails and the fish-plates, of a threadless bolt passing therethrough on either side of the rail-joint, and formed with the notch and the reduced end portion, a key working in said bolt and engaging the side of one of the fish-plates, and a spring-clamp fitting said reduced portion 65 of the bolt, and having a jaw engaging the notch, and another jaw exerting a constant pressure upon the key.

8. The combination with the rails and the fish-plates, each having elongated openings 70 on either side of the rail-joint, of a threadless bolt passing through each set of openings, and formed with the flattened portions *f*, *h* and the intermediate rounded portion *j*, a key working in said bolt and engaging the 75 side of one of the fish-plates, and means carried by the bolt exerting a constant pressure on the key.

9. The combination with the rails and fish-plates, of a threadless bolt passing therethrough on either side of the rail-joint, and formed with an opening partially overlapped 80 by one of said fish-plates, a key seated in the opening and bearing against said fish-plate, and means carried by the bolt exerting a constant pressure on the key.

10. The combination with the rails and fish-plates, of a threadless bolt passing therethrough on either side of the rail-joint, and formed with an opening *m* extending into the 90 opening in one of the fish-plates, the inner and outer end walls of said opening *m* being straight and inclined respectively, a key fitting the opening and having a straight edge and an inclined edge, and means carried by 95 the bolt exerting a constant pressure on the key.

11. The combination with the rails and the fish-plates, of a threadless bolt passing therethrough on either side of the rail-joint, a key 100 working in said bolt and engaging the side of one of the fish-plates, and a spring-clamp exerting a constant pressure on the bolt, and having a jaw struck up to form a recess into which the upper edge of the key is received. 105

In testimony whereof I affix my signature in presence of two witnesses.

THOMAS C. HACKETT.
